US0D1033028S

(12) **United States Design Patent** (10) **Patent No.:** **US D1,033,028 S**
(45) **Date of Patent:** **** Jul. 2, 2024**

(54) **INSOLE**

(71) Applicant: **PROTALUS LLC**, Tualatin, OR (US)

(72) Inventors: **Christopher Buck**, Tualatin, OR (US);
Calvin M. Buck, IV, Tualatin, OR (US)

(73) Assignee: **PROTALUS, LLC**, Tualatin, OR (US)

(**) Term: **15 Years**

(21) Appl. No.: **29/874,114**

(22) Filed: **Apr. 14, 2023**

Related U.S. Application Data

(63) Continuation of application No. 29/864,322, filed on May 20, 2022, now abandoned.

(51) **LOC (14) Cl.** **02-04**

(52) **U.S. Cl.**

USPC **D2/961**

(57) **CLAIM**

The ornamental design for an insole, as shown and described.

DESCRIPTION

FIG. 1 is a top perspective view of an insole showing our new design;

FIG. 2 is a bottom perspective view thereof;

FIG. 3 is a bottom plan view thereof;

FIG. 4 is a top plan view thereof;

FIG. 5 is a lateral elevation view thereof;

FIG. 6 is a medial elevation view thereof;

FIG. 7 is a rear elevation view thereof; and,

FIG. 8 is a front elevation view thereof.

The broken lines in the figures illustrate portions of the insole that form no part of the claimed design.

1 Claim, 8 Drawing Sheets
